CLAIM

The ornamental design for a sandal, as shown and described.

DESCRIPTION

FIG. 1 is a perspective view of a sandal of my new design.
FIG. 2 is a top plan view of the sandal of FIG. 1.

FIG. 3 is a bottom plan view of the sandal of FIG. 1.

FIG. 4 is a left side elevation view of the sandal of FIG. 1.

FIG. 5 is a right side elevation view of the sandal of FIG. 1.

FIG. 6 is a front end view of the sandal of FIG. 1; and,

FIG. 7 is a back end view of the sandal of FIG. 1.

The broken lines in the drawings are included for the purpose of illustrating unclaimed features and form no part of the claimed design.
